UNITED STATES PATENT OFFICE.

LEE O. GARRAWAY, OF MEMPHIS, TENNESSEE.

FEED-WATER HEATER FOR LOCOMOTIVE BOILERS.

Application filed October 8, 1925. Serial No. 61,297.

This invention relates to heaters for heating feed water for boilers, and particularly to heaters for use with locomotive boilers.

The primary object of this invention is to efficiently utilize the exhaust steam from a plurality of sources whereby to heat the feed water to the very highest temperature possible by the use of exhaust steam before the water enters the boiler, thereby eliminating the use of reservoirs or heaters that are ordinarily placed in or about boilers, the heaters containing therein a series or network of piping for circulating the exhaust steam around to heat the water before it enters the boiler.

A further object of the invention is to provide heating means in which the exhaust steam is led over the top of the locomotive through a wide and relatively shallow passage extending longitudinally of the boiler and underneath the asbestos lagging thereof and resting upon or in direct contact with the shell of the boiler to thereby conserve the heat and minimize its loss.

A still further object is to provide means for heating feed water which will reduce the expense of application and maintenance to a minimum, and in this connection to provide means for heating feed water which will be compact, simple and inexpensive and which may be readily applied to any boiler and by which the feed water supplied to the boiler will have its temperature raised to the highest degree possible by the use of exhaust steam.

My invention is illustrated in the accompanying drawings, wherein:—

Figure 1 is a side elevation of a locomotive of an ordinary type having my invention applied thereto;

Figure 2 is a front elevation of the boiler and cylinders of a locomotive provided with my heating system.

Figure 3 is a section on the line 3—3 of Figure 1;

Figure 4 is a vertical sectional view through one form of heater;

Figure 5 is a top plan view of the plate 27 shown in Figure 4; Figure 6 is a top plan view of the plate 26 shown in the same figure.

Figure 7 is a side elevation of the locomotive shown in Figure 1 but looking to the opposite side thereof;

Figure 8 is a sectional view through the

automatic valve controlling the heating of the water which passes through the injector.

In Figure 1, it will be seen that I have illustrated one side of an ordinary locomotive. This locomotive is illustrated as having the tender A provided with the usual water tank and as having the air pumps B, the water pump C whereby water is forced into the engine boiler, and the cylinders D having the usual valve chests or chambers d. None of these parts have any bearing upon my invention so far as their detailed structure goes.

Disposed between the pump C and the tender A is the water heater which in general I have designated E. The pump C takes water from this heater and pumps the water up through the pipe 10, past the check valve 11, and past the valve 12 into the boiler in the usual and ordinary manner. The exhaust steam which is utilized within the heater E is taken from a plurality of sources. Thus the exhaust steam from the pump C passes out through the pipe 13 which is carried along longitudinally of the boiler and communicated with a transverse pipe 15, which in turn communicates with the exhaust cavities of the chambers d. The pipe 15 into which the exhaust pipe 13 opens is provided with the usual controlling valve 16 and discharges into an oil separator 17. Extending from the exhaust port of the pump B is a pipe 14 which communicates with the pipe 13. From the separator 17 a pipe 18 extends upward and partially around the boiler and over the top of the boiler, and at 20 extends longitudinally and enters between the lagging 21 and the boiler shell. This pipe from the point 20 to the point 22 is flattened to provide a wide and shallow passage extending longitudinally of the boiler beneath the asbestos lagging 21 thereof and resting upon or in direct contact with the shell of the boiler. At 22 this relatively wide and shallow pipe extends out from the lagging and then extends to the heater E, as will be now described.

The heater E, as shown in Figure 4, consists of an outer casing of any desired shape having an inlet port 23 for water and an inlet port 24 for steam, which inlet port for steam connects to the pipe 20, as heretofore described, while the port 23 communicates by pipe 23a with the tank A. The heater casing

is formed to provide a chamber 25 more or less rectangular in cross section traversed by two transversely extending spaced webs 26 and 27, these webs being provided with apertures 28^a and 28, the apertures 28 in the web 27 being disposed to one side of a vertical plane extending diametrically through the heater casing, while the apertures 28^a in the web 26 are disposed around the center of the web 26. The port 23 opens into a spray head 29 having apertures 30. This spray head is disposed on a level with the port 24 and at its upper end is formed to provide a valve seat against which a valve 31 seats when the valve is raised, this valve being mounted upon a stem 32 which extends down through apertures in the webs 26 and 27 and carries at its lower end the float 33 which is very nearly as large as the chamber 25. The lower portion of this chamber 25 has a port 34 which leads to the intake valve casing 35 of the pump, there being a like valve casing and chamber 36 on the opposite side of the central, medially disposed piston chamber 37 of the pump.

In the use of the heater shown in Figure 4, the water from the hose 23^a will pass downward through the port 23 and, if the valve 31 be open, into the spray head 29 where it will be discharged through the apertures 30 both downwardly and laterally through the steam space 38 which forms the upper portion of the chamber 25. The exhaust steam will enter from the port 24 and the sprays will be discharged through this exhaust steam, condensing the exhaust steam and intermingling the exhaust steam with the feed water, and the steam and water will pass downward through the perforations in the baffle plates 26 and 27 and then into the lower portion of the chamber 25. As soon as sufficient water has accumulated in the heater, the float 33 will lift the valve 31 and prevent any more water entering the heater. As soon, however, as the level of water drops, the float valve will also drop, permitting the introduction of more water. Thus the water will always be kept at a constant level within the heater.

The exhaust steam, it will be noted, is condensed by the sprays which are discharged from the spray head and is intimately mingled with this water. The stream of exhaust steam and water, then passes to the side of the tank E opposite the inlet port 24 and down through the openings 28 onto the second plate or partition 26 and then across and then downward through the apertures 28^a, these being arranged at the center of the plate discharging the water onto the center of the float. The water runs off the float in a thin film and trickles down between the side of the tank and the float. By this arrangement the exhaust steam is condensed and thoroughly mixed and intermingled with the water and heats feed water.

On a locomotive, however, the stopping and starting of the train, the jolts and jars to which the train is subjected, the movement of the train down a grade, etc., all tend to cause water to surge from the tank A toward the heater, and it is to be particularly noted that in my construction, when the water surges from the tender A into the port 23, it will act to force the valve 31 downward to thus open the valve, but this opening of the valve to any appreciable extent is prevented by the fact that the float 33 is of such area as to very nearly fill the chamber 25 and as a consequence the water below this float offers a great impediment to the opening of the valve and assuming that the chamber 25 is nearly full of water, it can open, if at all, but very slightly and even if a slight amount of water enters through the port 23, this will cause the float to press upward with additional force, tightly closing the valve, so that when the chamber 25 has its full quota of water, there can be no further entrance of water even when the water surges in the tender. This is another very essential part of my mechanism, inasmuch as without this the level of water within the heater would constantly vary when the pump is in operation, there being an intermittent dropping of the float 33 and the valve and an intermittent upward movement of the valve and float. When the chamber 25 is filled to the proper level, there will be no downward movement of the valve due to the very large size of the float and the fact that this float very nearly fills the cylinder. I have illustrated the heater E as being provided with a relief valve 39 of common and ordinary form whereby any excess pressure of steam or other fluid in the upper portion of the chamber may be relieved.

In Figure 7, I show the opposite side of the locomotive from that shown in Figure 1, to illustrate the fact that I use in conjunction with the heating system shown in Figure 3 means for heating the feed water as it passes from the injector into the boiler, the heating means being exhaust steam taken from the pipe 20. In this figure, 40 designates the feed water pipe connected to the usual boiler intake port 41. 42 designates a water pipe connected by hose to the tender A and extending upward and entering the injector casing 43. This injector casing is of the usual construction and needs no particular illustration.

For the purpose of heating the feed water in the body of the injector 43, I provide the exhaust steam pipe 45 which connects to a valve casing 46, which valve casing is connected by a pipe 47 to the pipe 20, as at 48 (see Figure 1). Disposed within the valve casing 46 is a valve 49. This valve 49 controls the passage of exhaust steam into the body of the injector and attached to the

valve is a stem 50 which extends down through the casing 46 and into a float chamber 51 disposed in the length of the pipe 40 and between the injector 43 and a check valve 52. When the injector is put in operation by shifting the valve handle 53 so as to cause water to be injected into the boiler through the injector 43, the water, as soon as it reaches the chamber 51, acts to lift up on the float piston 54 disposed in said chamber and against the action of the spring 55, and this causes the opening of the valve 49 and exhaust steam will promptly flow into the body of the injector, and will be condensed thereby and will impart its heat to this feed water before it passes out of the injector into the branch pipe 40 and enters boiler at the usual boiler intake port 41.

In these constructions, I provide a means for heating the feed water of locomotives which takes its heating supply from the more or less wasted exhaust steam of three different sources of supply so that this exhaust steam is condensed and flows back into the boiler along with the feed water from the tank A and the feed water from the tank A is heated by the exhaust steam. The float 33 I regard as a very important feature of my invention inasmuch as this float maintains a predetermined level of water at all times within the heating and mixing chamber E. When the level of water gets below the predetermined amount, the float will fall, opening the valve 31 and allowing more water to flow into the heating and mixing chamber E. As soon as sufficient water has flowed into the chamber, the valve closes and cuts off the further passage of water. It is essential that the condensation and heating tank shall not be filled with water or flooded, and this I secure with the valve and float I have illustrated. All locomotive boilers are equipped with two water supplying devices and they are generally worked alternately on each trip by enginemen, and in the construction which I have illustrated, the feed water is raised in temperature from exhaust steam when the boiler is being supplied with water from either one or both of the water supplying devices.

While I have illustrated a construction which I believe to be particularly effective and which is peculiarly adapted to locomotive boilers for the reasons above stated, I do not wish to be limited to its use with a locomotive boiler, nor do I wish to be limited

to the exact construction illustrated as this might be changed in minor matters without departing from the spirit of the invention as defined in the appended claims.

I claim:

1. The combination with a locomotive having engine cylinders and steam chests therefor having exhaust ports, a discharge pipe connecting said ports and leading therefrom, a feed water pump disposed upon one side of the engine and having a water outlet connected to the boiler of the engine, and an air pump disposed on one side of the engine and having an exhaust port, of a feed water heater connected on one side to a source of water supply and on the other side to said water pump, an oil separator, an exhaust pipe leading longitudinally along the engine from the exhaust of said water pump, a pipe leading the exhaust from said port of the air pump to said longitudinally extending pipe, said longitudinally extending pipe being operatively connected through said discharge pipe to said oil separator, a pipe leading from the oil separator and passing upward and around the boiler of the engine, then extending longitudinally beneath the lagging of the boiler rearward and then downward and then extending out from beneath said lagging and then entering the heater for supplying exhaust steam from said sources for heating feed water in said heater.

2. In a locomotive, a steam condenser, means for carrying the steam to the steam condenser including a relatively shallow conducting pipe disposed immediately against the shell of the boiler and extending under the jacket and asbestos lagging thereon, and means for conducting exhaust steam to said conducting pipe.

3. In a locomotive having a boiler, a jacket and asbestos lagging over the boiler, means for condensing exhaust steam including a condenser connected to means whereby the water therefrom may be forced into the boiler of the engine, a pipe leading from a source of exhaust steam to said condenser including in its length a relatively wide and shallow duct disposed against the boiler and beneath the jacket and asbestos lagging and extending longitudinally of the boiler and then downward over the boiler.

In testimony whereof I hereunto affix my signature.

LEE O. GARRAWAY.
